UNITED STATES PATENT OFFICE.

NEWMAN H. HOLLAND, OF WEST ORANGE, NEW JERSEY, ASSIGNOR, BY MESNE ASSIGNMENTS, TO NEW JERSEY PATENT COMPANY, OF WEST ORANGE, NEW JERSEY, A CORPORATION OF NEW JERSEY.

PHONOGRAPH.

1,092,911.

Specification of Letters Patent. Patented Apr. 14, 1914.

Application filed March 13, 1911. Serial No. 614,278.

To all whom it may concern:

Be it known that I, NEWMAN H. HOLLAND, a subject of the King of Great Britain, and a resident of Llewellyn Park, West Orange, 5 in the county of Essex and State of New Jersey, have invented certain new and useful Improvements in Phonographs, of which the following is a specification.

My invention relates to phonographs and 10 more particularly to new and improved means whereby the record of a phonograph may be readily disengaged from its support without damage to the record surface.

As ordinary phonograph records change 15 in diameter to a considerable extent under different temperature conditions, expanding under heat and contracting under cold, and as the supports upon which the records are mounted change but little in diameter under 20 the same conditions and are so constructed that when the records are slipped thereon, a tight engagement will be maintained between the same and the records, it frequently happens that the latter become so tightly 25 locked to their supports that it is practically impossible to remove them by hand without damage to them.

It is the principal object of my invention to overcome this difficulty by providing 30 improved means for automatically loosening the record from its support so as to permit it to be readily removed by hand. In conformity with this object, I preferably provide a movable record support and means 35 mounted in proximity thereto for shifting the record relatively to the said support when the mandrel is moved from its normal position.

Other objects of my invention consist in 40 the construction of parts and combinations of elements as will be more particularly pointed out in the claims.

In order that my invention may be more 45 fully understood, attention is hereby directed to the accompanying drawing forming a part of this specification, and in which:

Figure 1 represents a vertical longitudinal section through the center of the mandrel of a phonograph embodying my invention; 50 Fig. 2 represents a similar view of a modification; and Fig. 3 represents a plan view of the left hand end of the mandrel.

In all of the views, corresponding parts

are designated by the same reference numerals.

Referring to Fig. 1, 1 represents a bed plate provided with a standard 2 in which the shaft or bearing 3 of the mandrel or record support 4 is fixedly secured by a set screw or other securing means 5. The mandrel 4 is mounted to rotate and to slide axially on the shaft or bearing 3 and is provided at its ends with members 6 and 7, which are in turn provided with bushings 8 and 9 respectively engaging the periphery 60 of the shaft 3. The free end of the latter is preferably offset or enlarged as shown at 3', and the bushing 9 is made to extend to the left of the member 7 a short distance so as to permit a considerable relative axial movement between the mandrel and its bearing without disengaging the bushing 9 from the shaft 3. 65 Member 7 is an air passage adapted to permit the passage of air into and out of the cylinder formed by the member 7 and the bushing 9 during the reciprocation therein of the offset end 3' of the shaft. Rotatably mounted on the shaft 3 but held from axial movement thereon by a set 70 screw 10 coöoperating with a circumferential groove 11 in the said shaft is a friction disk 12 driven from any suitable motor (not shown) by a friction member 13. The disk 12 is provided with a bushing 14 engaging 75 the periphery of the shaft 3. As shown in the drawing, this bushing is held against movement relatively to the member 12 by the set screw 10, but obviously it could be secured to the said member by friction or in 80 any other suitable way. The rotation of the disk 12 is transmitted to the mandrel 4 by a member 15 secured to the bushing 14, the said member being provided with an annular flange 16 having one or more longitudinal 85 slots 17 therein. Pins or projections 18 preferably secured to the member 6 coöperate with said slots and are adapted to slide 90 therein when the mandrel is shifted along the shaft or bearing 3. The pins 17 and 100 slots 18 thus serve as means for transmitting the rotation of the driving means to the mandrel and at the same time as a guide for the mandrel during the axial movement thereof. The outer edge 19 of the flange 16 105 extends over and in close proximity to the

record bearing surface of the mandrel; so that as the mandrel is moved to the left, the left hand edge of the record is engaged by the said flange and is disengaged from the mandrel. A compression spring 20, preferably a coil spring surrounding the shaft 3, bears against the opposing faces of the members 6 and 15, so as to cause the mandrel to automatically return to its normal position after it has been displaced therefrom. This spring is preferably designed to be under a slight compression when the pins 18 are in engagement with the right hand end of the slots 17 and are thus held in place by 10 and rotate with the members 6 and 15. The numeral 21 represents a gear secured to the driving means and adapted to be connected with suitable means (not shown) for feeding the reproducer (not shown) along the 15 record.

In operating my improved device, the mandrel is given a quick thrust to the left, whereby the record is disengaged from and shifted longitudinally of the mandrel by 20 the abutment or flange 16, so that it may then be readily removed by hand, the spring 20 returning the mandrel to its normal position. With the modification shown in Fig. 1, the movement of the mandrel to the left 25 is produced by direct application of force to the right hand end of the mandrel, preferably by hand.

Fig. 2 shows my improved device provided with means to impart an axial thrust 30 to the mandrel. This means comprises a hollow tubular member 22 mounted on the outer end of the shaft 3, which latter extends through the member 7 and preferably slightly beyond the same. The member 22 35 is provided with an inclined slot 23 in which is slidably engaged the pin or projection 24 secured to the shaft 3; and the left hand edge of the said member 22 engages the opposing end of the mandrel, so that as the 40 said member is rotated by the knurled head 25, it is shifted longitudinally of the shaft or bearing 3 and carries the mandrel with it.

While I have shown certain preferred embodiments of my invention, I do not wish 45 to be limited to those disclosed; as my invention may evidently be carried out in numerous other ways. Any desired member adapted to loosen the record from its support upon the displacement of the latter may 50 be substituted for the abutments shown; and, in short, my invention is limited only as defined by the terms of the appended 55 claims.

Having now described my invention, what 60 I claim as new and desire to secure by Letters Patent of the United States, is as follows:—

1. In a phonograph, a shaft, means supporting the same, a record support mounted 65 on said shaft and movable axially thereof,

and means mounted on said shaft in proximity to said record support and adapted to shift a record mounted on said support relatively to the latter when said support is moved axially of said shaft, substantially as 70 described.

2. In a phonograph, a rotatable record support, a bearing therefor, and means for rotating said record support, said support being movable with respect to said means 75 and said means being adapted to shift the record relatively to the said support when the latter and said means are moved relatively to each other, substantially as described.

3. In a phonograph, the combination of a rotatable record support, a bearing therefor, a member rotatable with said record support, said record support being movable relatively to said member, and said member being provided with an abutment adapted to shift the record relatively to the record support when the latter is moved in a given direction relatively to said member, and means for returning said record support to its normal position relatively to said member, substantially as described.

4. In a phonograph, the combination of a rotatable record support, a bearing therefor, a member rotatable with said record support, said support being axially movable relatively to said member, and said member being provided with an abutment adapted to shift the record relatively to the record support when the latter is moved in a given direction relatively to said member, and means for returning said record support to its normal position relatively to said member, substantially as described.

5. In a phonograph, the combination of a 105 rotatable record support, a bearing therefor, a driving member for said record support, said driving member and record support being movable relatively to each other, and said driving member being provided with an 110 abutment adapted to shift the record relatively to the record support when the latter and said driving member are moved toward each other, and yielding means for returning 115 said driving member and said record support to their normal relative positions, substantially as described.

6. In a phonograph, the combination of a record support, a shaft extending axially thereof, means coaxing with said shaft and support to move the same relatively to each other, and means for shifting a record mounted on said support relatively to the latter when said shaft and support are moved relatively to each other, substantially 120 as described.

7. In a phonograph, the combination of a record support, a bearing therefor, an abutment mounted in proximity to the record supporting surface of said record support, 125

and means for moving said support and abutment relatively to each other to shift the record relatively to the record support, said means comprising a rotatable member engaging said support and having an inclined pin and slot connection with said bearing, substantially as described.

8. In a phonograph, the combination of a rotatable record support, a shaft along which said support is axially movable, and means mounted on said shaft in proximity to said support adapted to shift the record relatively to said support when the latter is moved axially, substantially as described.

15 9. In a phonograph, the combination of a rotatable record support, a bearing therefor, and a member rotatable with said record support, said record support being movable relatively to said member, and said member being provided with an abutment adapted to shift the record relatively to the record support when the latter is moved in a given direction relatively to said member, substantially as described.

25 10. In a phonograph, the combination of a movable record support, means for supporting the same, means mounted in proximity to the record support and adapted to shift the record relatively to said support when the latter is moved from its normal position, and means for automatically moving said support back to its normal position directly upon the cessation of the force moving the same from said position, substantially as described.

35 11. In a phonograph, the combination of a rotatable axially movable record support, means for supporting the same, means mounted in proximity to the record support and adapted to shift the record relatively to said support when the latter is moved axially from its normal position, and means for automatically moving said support back to its normal position directly upon the cessation of the force moving the same from said position, substantially as described.

45 12. In a phonograph, the combination of a rotatable axially movable record support, means for supporting the same, means mounted in proximity to the record support and adapted to shift the record relatively to

said support when the latter is moved axially from its normal position, and resilient means for automatically moving said support back to its normal position directly upon the cessation of the force moving the same from said position, substantially as described.

55 13. In a phonograph, the combination of a rotatable record support, a bearing therefor, and a driving member for said record support, said driving member and record support being movable relatively to each other, and said driving member being provided with an abutment adapted to shift a record mounted on said support relatively to the latter when said support and said driving member are moved in a given direction relatively to each other, substantially as described.

60 14. In a phonograph, the combination of a record support, a shaft extending longitudinally thereof, means coacting with said shaft and support to move said support relatively to said shaft, and means for shifting a record mounted on said support relatively to the latter when said support is moved in a given direction relatively to said shaft, substantially as described.

65 15. In a phonograph, the combination of a shaft, a record support mounted thereon, means coacting with said shaft and support to move the same relatively to each other, and means for shifting a record mounted on said support relatively to the latter when said shaft and support are moved relatively to each other, substantially as described.

70 16. The combination of a record support, a shaft extending longitudinally thereof, means coacting with said shaft and support and rotatable to move the same relatively to each other, and means for shifting a record mounted on said support relatively to the latter when said shaft and support are moved relatively to each other, substantially as described.
